DOOR STRUCTURE FOR SILOS

Maurice W. Mott, Red Creek, N. Y.

Application April 22, 1938, Serial No. 203,696

3 Claims. (Cl. 20—1.4)

This invention relates to a combined hinged and continuous door structure designed primarily for wood or concrete silos, but it is to be understood that a door structure in accordance with 5 this invention is for use in any connection for which it may be found applicable.

The invention has for its object to provide, in a manner as hereinafter set forth, a continuous door structure for silos including a series of independently adjustable, latchable, hinged closure units capable of being respectively arranged in superposed relation for closing the silo; foldable back against the inside of the silo and completely out of the way when adjusted to open the silo; 15 and/or easily lifted off of their hinges for storage elsewhere if desired.

A further object of the invention is to provide, in a manner as hereinafter set forth, a continuous door structure including a series of independently adjustable, latchable closure units for disposing in superimposed relation and having the joints therebetween and with the silo of ship-lap construction providing, when said units are in closure position, a perfectly smooth substantially continuous surface between said units, and also between the units and the wall of the silo on the inside of the latter, resulting in the elimination of door bending, leakage and spoilage around door joints so often experienced with 25 other type doors for silos.

A further object of the invention is to provide in a manner as hereinafter set forth, a continuous door structure for silos including a pair of spaced, parallel door jambs, a series of continuous adjustable, removable closure units for disposing in superimposed relation and alternately hinged to said jambs, normally horizontally disposed spaced superposed swingable step members on the outer faces of said jambs, spaced, fixed, 30 superposed jamb spreaders bearing against the inner edges of and connected to the outer faces of the jambs and alternately disposed in spaced relation with respect to said members, and latching means for the units carried by the spreaders, 35 the construction and arrangement of the structural features aforesaid being such that when three successive units are opened from a position of superimposed relation and a step member swung downwardly from horizontal position, 40 there is ample space for a man to enter the silo between a pair of superposed jamb spreaders.

A further object of the invention is to provide, in a manner as hereinafter set forth, a continuous door structure for silos including step members, combined door jambs and step elements,

and adjustable closure units for disposing in superimposed relation rearwardly of said members and elements to close the silo, and with said elements and units including coacting means for firmly and detachably holding said units in superimposed relation when in closure position.

Further objects of the invention are to provide, in a manner as hereinafter set forth, a continuous door structure for the purpose referred to which is comparatively simple in its construction and arrangement, strong, durable, thoroughly efficient in its use, conveniently adjustable, readily set up, and comparatively inexpensive to manufacture.

Embodying the objects aforesaid, and to others which may hereinafter appear, the invention consists of the novel construction, combination and arrangement of parts as will be more specifically described and illustrated in the accompanying drawings, wherein is shown an embodiment of the invention, but it is to be understood that changes, variations and modifications may be resorted to which fall within the scope of the invention as claimed.

In the drawings:—

Figure 1 is a front elevation, broken away of the continuous door structure,

Figure 2 is a fragmentary view, in rear elevation of the door structure,

Figure 3 is a fragmentary view, in front elevation and upon an enlarged scale of the door structure,

Figure 4 is a section on line 4—4 Figure 3,

Figure 5 is a section on line 5—5 Figure 3,

Figure 6 is a section on line 6—6 Figure 3,

Figure 7 is a fragmentary view in front elevation and upon an enlarged scale illustrating a pair of closure units in adjusted position,

Figure 8 is a section on line 8—8 Figure 7 with the upper step omitted, and

Figure 9 is a front elevation and upon an enlarged scale of one of the adjustable closure units detached.

The continuous door structure includes a pair of spaced parallel vertically disposed jambs 10, 45 11 of the desired height and which coact to provide a door opening 12. The jambs are suitably secured to the silo body, not shown. The width and thickness of the jambs are to be as desired. The jambs will be partly countersunk in the inner face of and extend from the top to a point in proximity to the lower end of the silo body. The jambs will be arranged relative to the side edges of the opening in the silo body in a manner whereby the inner lengthwise edges of the jambs 50 55

will be disposed in spaced relation to said side edges. This arrangement may be had by rabbeting the portions of the inner face of the silo body bordering the opening in the latter, seating the jambs in and having the latter of a width to extend laterally in opposite directions from the rabbets. The jambs are of like form and each of which has the inner marginal portion of its inner lengthwise edge 13 provided with a section 14 of a ship-lap joint. The joint sections 14 are oppositely disposed. Each ship-lap joint section 14 is provided by forming the inner side marginal portion of the rear surface of a jamb lengthwise thereof with a rabbet.

15 The door structure includes two sets of adjustable closure units. The units of one set are indicated at 15 and the units of the other set at 16. The units of the said sets are arranged in alternately disposed relation. As shown by way of example the units 15 are to be adjusted to the right and the units 16 to the left when access is desired to be had to the silo. It is to be understood that the units 15 may be set up to be adjusted to the left and the units 16 to the right. 20 25 Each closure unit is of like form and includes a rectangular panel 17 of any suitable material, preferably wood. The side edges of the panel 17 are formed in a manner to provide a pair of oppositely disposed ship-lap joint sections 18 for coaction with the joint sections 14 when the panel is in closure position, as shown by Figures 4 and 5. The ship-lap joint sections 18 are provided by forming the side marginal portions of the front surfaces of the panels with oppositely disposed 30 35 transversely extending rabbets. The top and bottom edges of the panel are formed with oppositely disposed ship-lap joint sections 19, 20. The joint section 19 of a lower panel is for coaction with the joint section 20 of an upper panel when the panels are in closure position as shown by 40 45 Figure 6. The ship-lap joint sections 19, 20 are provided by forming respectively the top and bottom marginal portions of the front surface of the panels with oppositely disposed horizontally extending rabbets. The sections of the ship-lap joints are so formed that when they are in coacting relation there is provided a perfectly smooth substantially continuous surface between the said units and also between the units and the body of the silo on the inner side of the latter for 50 obtaining the advantages aforesaid.

Each of the units 15 includes a removably mounted hinged suspension 21 therefor arranged on the front face of its panel 17. Each of the units 16 includes a removably mounted hinged suspension 22 therefor arranged on the front face of its panel 17. When the units are in superimposed relation, that is in closure position, the suspensions 21 are superposed and the suspensions 22 superposed. The suspensions 21 are oppositely disposed with respect to the suspensions 22. The suspensions 21 are arranged on one side of the units 15 and the suspensions 22 on one side of the units 16 which is opposite the side of the units 15 on which the suspensions 21 are arranged.

The suspensions for the said units are of skeleton-like form and each consists of a top member 23 formed with a rearwardly extending angularly disposed inverted L-shaped depending inner end terminal portion 24 and an angularly disposed upwardly extending outer end terminal portion 25, a bottom member 26 having a rearwardly extending angularly disposed inverted L-shaped depending inner end terminal portion 27

and an angularly disposed upwardly extending outer end terminal portion 28, an outer side member 29 arranged between and integral with the members 23, 26 and spaced inwardly from the end terminal portions 24, 27, and an inner side member 30 arranged between and integral with the members 23, 26 at the points of emergence of the terminal portions 24, 27 with the remaining parts of the members 23, 26. The vertical legs 31 of the end terminal portions 24, 27 vertically align and provide pivots. The end terminal portions 25, 28 vertically align and provide pivots. The member 29 is flat and of rectangular cross section and constitutes a keeper for a latching member to be referred to. 15

Secured to the front face of each of the panels centrally thereof is a pair of horizontally disposed spaced vertically aligned short straps 32, 33 bent upon themselves at one terminal portion thereof to form vertically disposed barrels 34, 35 respectively. The said end terminal portions 25, 28 removably extend into and coact with the barrels 34, 35 to form a pair of outer hinged connections between a panel 17 and one end of a suspension. Each hinged connection is formed of a pair of interengageable parts capable of being separated. The barrels 34, 35 which coact with the suspensions 21 are disposed on the ends of the straps 32, 33 opposite the ends of the latter on which those barrels 34, 35 are arranged which 30 35 coact with the suspensions 22. The straps 32, 33 are arranged above the members 23, 26 respectively of a suspension.

Secured to the outer face of the jamb 10 are superposed spaced pairs of spaced angle-shaped 35 straps 36 for coaction with the suspensions 22. Each strap 36 is formed of an outer leg 37 and an inner leg 38 extending inwardly at right angles to the inner end of leg 37 and opposing the edge 13 of the jamb 10. The leg 38 is bent upon itself 40 to form a vertical barrel 39. The straps 36 of each pair are arranged below the members 23, 26 of a suspension 22. The end terminal portions 25, 28 of a suspension 22 removably extend into the barrels 39 of a pair of straps 36 to form a pair of 45 inner hinged connections between the jamb 10 and the other end of a suspension 22. Each hinge connection between a suspension 22 and the jamb 10 is formed of a pair of interengagable parts capable of being separated. 50

Secured to the outer face of the jamb 11 are superposed spaced pairs of spaced angle shaped straps 40 for coaction with the suspension 21. Each strap 40 is formed of an outer leg 41 and an inner leg 42 (Figure 8) extending inwardly at 55 right angles to the inner end of leg 41 and opposing the edge 13 of the jamb 11. The leg 42 is bent upon itself to form a vertical barrel 43. The straps 40 of each pair are arranged below the members 23, 26 of a suspension 21. The end 60 terminal portions 25, 28 of a suspension 21 removably extend into the barrels 43 of a pair of straps 40 to form a pair of inner hinge connections between the jamb 11 and the other end of a suspension 21. Each hinge connection between a suspension 21 and the jamb 11 is formed of a pair of interengagable parts capable of being separated. 65

The manner of setting up the straps 32, 33, 36 and 40 relative to the suspensions permit of the 70 panels being swung inwardly to oppose the inner face of the body of the silo. The panels of the units 15 are to be swung to the left and the panels of the units 16 are to be swung to the right. A further provision is had whereby the suspen- 75

sions may be expeditiously separated from the jambs and from the panels.

The door structure includes a set of superposed adjustable step-forming members 44 which when in normal position are disposed horizontally and extend when in normal position from the jamb 10 to the jamb 11. The members 44 oppose the outer faces of the units 16 when these latter are in closure position. The members are of like construction and each consists of a bar 45 having an angularly disposed depending end terminal portion 46 which loosely extends into a barrel 47 from the lower end of the latter. The barrel 47 is integral with a carrier 48 therefor pivotally connected, as at 49 to the front of jamb 10. Secured to the front of jamb 11 are superposed angle-shaped keepers 50, each associated with the other end terminal portion 51 of a member 44 to detachably support the latter in the position shown in Figures 1, 3 and 4, that is extending horizontally and across a unit 16.

The door structure includes a set of superposed horizontally disposed combined step forming and jamb spreading elements 52 of like form and each of which extends from jamb 10 to jamb 11. The elements 52 when the units are in closure position oppose the outer faces of the units 15, as is shown in Figures 1 and 3. The elements 52 are permanently secured to the jambs 10, 11 and are alternately disposed with respect to the members 44. The elements 52 are of like construction and each consists of an outwardly opening channel shape portion 53 forming a wide foot tread and a pair of oppositely disposed tapered end portions 54, 55 formed at their inner ends with inwardly extending flanges 56, 57 respectively providing abutments. The inner wall of the portion 53 merges at its ends into the inner ends of the end portions 54, 55. The top and bottom walls of the portion 53 are extended on and merge into the front face of the portions 54, 55. The inner end parts of the portions 54, 55 are of greater width than the height of portion 53 whereby the ends of the latter will be spaced inwardly from the top and bottom edge of said portions 54, 55. The top and bottom walls of the portion 53 are connected to the portions 54, 55 by the web 58. The portions 54, 55 are secured to the jambs 10, 11 by the holdfast devices 59a. The flanges 56, 57 are arranged against the edges 13 of the jambs 10, 11 whereby these latter are maintained in spaced relation.

The door structure includes a set of latching members 59a, each of which is pivotally connected against the inner face of an element 52 and consisting of a shank 60 terminating at one end into a handle 61. The shank 60 at its other end has one side edge thereof formed with an angle-shaped nose 62 disposed at right angles thereto. The nose 62 is formed of a pair of legs 63, 64 extending at right angles to each other. Each latching member 59a is for coacting with a suspension 21 of a unit 15 for latching the latter in closure position. When a latching member 59a is in active position the leg 63 thereof is arranged rearwardly of the side member 29 of a suspension 21, the leg 64 abutting a lengthwise edge of such side member and the handle 61 seated on the top wall of the intermediate portion 53 of an element 52 and in this connection attention is directed to Figure 5. The said side member 29 coacts with a latching member 59a to form a keeper for the nose 62 and prevent a unit 15 being swung inwardly from its closure position

shown in Figure 5 until the latching member has been swung to the position shown in Figure 7.

When the units 15, 16 are disposed in superimposed or closure position, such as shown in Figures 1 and 2, and when the latching members 59a are active the units 16 are latched to the units 15 and the units 15 are latched to the elements 52 they will be held in such position until the units 15 are released. When an upper latching member 59a is released it unlatches an upper unit 15 and the lower unit 16 directly below such unit 15. The ship-lap joints between a unit 16 and the pair of units 15, between which unit 16 is arranged prevents the opening of unit 16 until the upper unit of the said pair of units 15 is unlatched and further acts to prevent the opening of the lower units 15 of the said pair of units 15, even if such lower unit is unlatched until the upper unit 15 of the said pair of units 15 is unlatched.

When a set of three superimposed units are opened and the step members 45 which extend across the central unit of such set is dropped to the dotted line position, Figure 2, there is ample room, between the elements 52 which extend across the outer units of said set for a man to enter the silo.

What I claim is:

1. In silos, a pair of parallel spacer jambs providing a door opening, each of said jambs having the rear portion of its inner side edge formed with stepped rabbets, independently shiftable continuous closures for disposing in superimposed overlapping relation in said opening and for seating in the rabbets of said jambs, the abutting edges of each pair of superimposed closures being rabbed to provide for the overlapping of such closures, the side edges of each closure being rabbed to provide for the closure seating in the rabbets of the jambs, spaced inner pairs of spaced pivot receivers, each pair being secured to the front face of a closure, superposed spaced outer pairs of spaced pivot receivers secured to the front face and extending inwardly from the inner side edge of each jamb, each pair of outer pivot receivers correlated with and arranged below the receivers of an inner pair, suspension means for each closure, each suspension means being formed with oppositely disposed pivots for mounting in the correlated pairs of receivers to provide in connection with the latter a hinge connection between a closure and a jamb, and superposed spaced combined step formers and spreader elements extending across each alternate closure, said elements being secured to the front faces and bearing against the inner side edges of the jambs.

2. In silos, a pair of parallel spaced jambs providing a door opening, each of said jambs having the rear portion of its inner side edge formed with stepped rabbets, independently shiftable continuous closures for disposing in superimposed overlapping relation in said opening and for seating in the rabbets of said jambs, the abutting edges of each pair of superimposed closures being rabbed to provide for the overlapping of such closures, the side edges of each closure being rabbed to provide for the closure seating in the rabbets of the jambs, spaced inner pairs of spaced pivot receivers, each pair being secured to the front face of a closure, superposed spaced outer pairs of spaced pivot receivers secured to the front and extending inwardly from the inner side edge of each jamb, each pair of outer pivot receivers correlated with and arranged below the receivers of an inner pair, suspension means for each clo- 75

- sure, each suspension means being formed with oppositely disposed pivots for mounting in the correlated pairs of receivers to provide in connection with the latter a hinge connection between a closure and a jamb, superposed spaced combined step formers and spreader elements extending across each alternate closure, said elements being secured to the front faces and bearing against the inner side edges of the jambs, and shiftable means carried by said elements for latching the said alternate closures in closed position whereby the other of said closures will be releasably held in closed position by the alternate closures.
3. In silos, a pair of parallel spaced jambs providing a door opening, each of said jambs having the rear portion of its inner side edge rabbeted, independently shiftable continuous closures for disposing in superimposed overlapping relation

in said opening and for seating in the rabbets of said jambs, the abutting edges of each pair of superimposed closures being rabbeted to provide for the overlapping of such closures, the side edges of each closure being rabbeted to provide for the closure seating in the rabbets of the jambs, means for hinging and suspending certain of the closures to and from one of the jambs, means for hinging and suspending the others of the closures to and from the other of the jambs, superposed spaced stationary combined step formers and spreader elements extending across each alternate closure, said elements being secured to the fronts of said jambs, and shiftable means carried by said elements for latching the said alternate closures in closed position whereby the other of the said closures will be releasably held in closed position by the alternate closures.

MAURICE W. MOTT.
